W. BARTHOLOMAE

MUSICAL TOY

Filed June 1, 1925

Fig. 1.

UNITED STATES PATENT OFFICE.

WILLIAM BARTHOLOMAE, OF BROOKLYN, NEW YORK, ASSIGNOR TO BAR-ZIM TOY MFG. CO., INC., OF NEW YORK, N. Y., A CORPORATION OF NEW YORK.

MUSICAL TOY.

Application filed June 1, 1925. Serial No. 34,203.

To all whom it may concern:

Be it known that I, WILLIAM BARTHOLOMAE, a citizen of the United States of America, and a resident of the borough of Brooklyn, in the city of New York, county of Kings, and State of New York, have invented certain new and useful Improvements in Musical Toys, of which the following is a specification, reference being had 10 to the accompanying drawings, forming part thereof.

This invention relates to improvements in musical toys and particularly to improvements in that type or kind of musical toys 15 in which there are provided several sounding elements in the form of bars or the like that have been given various forms or shapes heretofore. In playing prior musical toys of this general class, the sounding elements 20 have been tapped with the ball shaped end of a small stick. An object of this invention resides in the provision of a musical toy of this type having sounding elements that are designed and adapted to be 25 lightly rubbed, from end to end, with a side- 30 wise stroke crosswise of the toy, whereby there may be produced music that has been likened to the sounding of chimes. To this end, the face of the sounding elements that 35 is arranged to be touched by the player's stick is given a ridged surface, which may be produced in various ways, some of which are hereinafter described. Another object of this invention lies in the provision of the 40 sounding elements with lips, by the formation of which the note given forth by the element is varied and improved. A third object of this invention consists in the novel and improved mounting provided for the 45 sounding elements in the frame or base of the toy. Other features of this invention will be brought out as the description progresses.

In the drawings illustrating the principle 50 of this invention and the best mode now known to me of applying that principle, Fig. 1 is a plan view of the musical toy, parts being shown broken at A; Fig. 2 is a fragmentary side elevation; Fig. 3 is a trans- 55 verse section on the line 3-3, of Fig. 1; Figs. 4, 5 and 6 are detail views illustrating, in section, sounding elements provided with lips that are differently formed; Fig. 7 is a detail view illustrating, in section, a frag- 60 ment of a sounding element, the rubbing or

stroking face of which is formed with corrugations; Fig. 8 is a detail view illustrating, in perspective, a modified form of sounding element; and Fig. 9 is a detail illustrating still another form of ridged playing face 60 of a sounding element.

As will be seen from an inspection of Fig. 1, the base or support B is, in plan view, trapezoidal in form, the end-blocks a, b, lying parallel to each other, while the side-walls c, d, converge towards each other so that the end-block a is smaller than the other end-block b. The side-walls c, d, are, at their bottoms, formed with inwardly-turned flanges c', d', the edges c'', d'', of which are finished off by being doubled back upon the flanges c', d'. Along their tops, the side-walls c, d, are formed with recesses e arranged to receive the sounding or music-emitting elements f. The recesses e are 70 separated by upstanding lugs or posts g, the upper ends of which are formed with guide-loops or eyes g'. As shown in Figs. 2 to 6, inclusive, the sounding elements f have a substantially inverted U-shape in end view 75 and cross-section, and the walls h that extend lengthwise of the sounding element f and downwardly from the playing (or rubbing) surface i thereof, are formed with holes j that are arranged to receive a cord k 80 that is threaded through the eyes g' and that passes outside of the end-block b and the ends of which are held by the button m that is carried by the other end-block a. 85 This mode of suspension of the sounding 90 elements f reduces damping of the vibrations and results in the tone emitted being more sustained and more pure.

I have discovered that an improved tone is 95 obtained from the extending element f, when its lengthwise and downwardly extending walls h are formed with lips, which may be bent from the walls h as is shown at h' (Fig. 2), or at h'' (Fig. 4). Or these lips 100 may be curved inwardly as at h^x (Fig. 5), or they may be curved outwardly, as at h^{*} (Fig. 6).

An important feature of this invention resides in the provision of the top or playing face i with a ridged surface, which the player strokes or rubs with the ball-shaped end of his playing stick (or a like device). 105 This ridged or wavy surface may be given to the playing face i in various ways; e. g., the ridged contour may be produced by 110

forming a series of raised portions or protuberances i'' (Figs. 2 and 3) that are spaced from one another, so that a musical tone or note is emitted by the sounding element f when the playing stick is stroked or passed lightly over the prominences i'' of the playing surface i of the element f from end to end thereof or transversely of the toy-base B. Or, as is shown in Fig. 7, the playing face of the element f'' may be ridged by forming it with alternate swells i'' and valleys i'' , that is, it may be wrinkled or corrugated. In Fig. 8, the sounding element f' has a playing face i that is ridged by forming it with a series of prominences or bosses n that are separated by the grooves n' and are flattened at their tops n'' . In Fig. 9, the playing face i of the element f'' is given a ridged or bossed contour by the provision of the rounded humps or teats o . In all these cases, the spaced ridge-forming prominences are of such slight elevation above the level of the playing face i as to permit the musical sounds to be produced by wiping the ridged playing face i of the sounding elements f , f' , f'' , f'' , with the playing stick in an unobstructed or uninterrupted (that is, continuous) rubbing across-stroke from end to end of these elements over the spaced ridge-forming prominences.

In accordance with the patent statutes, I have shown and described the preferred form of this invention; but I desire it to be distinctly understood that I fully realize that changes may be made in the structure herein disclosed, and that I intend to include within the scope of the claims that follow hereinafter all modifications of the preferred form of this invention that do not depart substantially from the spirit thereof. For example, instead of flattening the tops n'' of the ribs n (Fig. 8), the tops of the latter may be made more or less sharp, so

that they will give the playing face i a toothed or notched contour; that is, the ridged playing face i may be serrated.

In the claims that follow, the elements f are described as music-emitting elements and so are distinguished from frame-forming or supporting elements, such as the channel-bars a , c , of my prior Patent, No. 1,024,878.

I claim:

1. A musical toy having music-emitting elements of varying pitch the playing-faces of which elements are ridged by low-lying, spaced prominences and arranged to emit musical sounds when stroked with a playing-stick; such prominences being of music-producing quality and having such slight elevation above the playing-faces as to afford the playing-stick free passage in a rubbing music-producing stroke lengthwise of the elements and over the prominences. 65

2. A musical toy the music-emitting elements of which are channeled and have side-walls that are formed with lips.

3. A musical toy including a base-support formed with recesses; music-emitting elements arranged in the recesses, said elements being U-shaped in cross-section, forming lateral walls which are perforated; and a cord that is rove through the holes in the lateral walls of the elements and that secures the latter to the base-support and supports them in the recesses. 75

4. A musical toy having music-emitting elements of varying pitch; the playing faces of said elements being ridged and arranged to emit musical sounds when stroked with a playing stick over the inequalities of the ridged playing surfaces; such inequalities being of music-producing quality and affording the playing stick free passage in 85 a rubbing music-producing stroke.

WILLIAM BARTHOLOMAE
